CLAIM

The ornamental design for a cleaning brush with a color scheme for household inanimate surfaces and fabric, as shown and described.

DESCRIPTION

FIG. 1 is a perspective view for a cleaning brush with a color scheme for household inanimate surfaces and fabric showing our new design.

FIG. 2 is a front view of the cleaning brush with a color scheme for household inanimate surfaces and fabric of FIG. 1.

FIG. 3 is a side view of the cleaning brush with a color scheme for household inanimate surfaces and fabric of FIG. 1.

FIG. 4 is a rear view of the cleaning brush with a color scheme for household inanimate surfaces and fabric of FIG. 1.

FIG. 5 is a top view of the cleaning brush with a color scheme for household inanimate surfaces and fabric of FIG. 1; and, FIG. 6 is a bottom view of the cleaning brush with a color scheme for household inanimate surfaces and fabric of FIG. 1.

With respect to the drawings, stippled surface shading is used to represent one color while line shading is used to represent a second different color. The broken line showing of environmental structure in the drawings is for illustrative purposes only and forms no part of the claimed design.
